(57) **CLAIM**

The ornamental design for an earbud charging case as shown and described.

DESCRIPTION

1. Earbud charging case

1.1 : Front

1.2 : Back

1.3 : Left

1.4 : Right

1.5 : Top

1.6 : Bottom

1.7 : Perspective

1.8 : Perspective

Reproduction 1.1 is a front view of an earbud charging case showing our new design; reproduction 1.2 is a rear view thereof; reproduction 1.3 is a left side view thereof; reproduction 1.4 is a right side view thereof; reproduction 1.5 is a top view thereof; reproduction 1.6 is a bottom view thereof; reproductions 1.7 and 1.8 are perspective views thereof.

(Continued)

The broken lines shown in the Reproductions show portions of the earbud charging case that form no part of the claimed design.

1 Claim, 8 Drawing Sheets
